JAMES CORNELL GAYNOR, OF PATERSON, NEW JERSEY.

WOVEN TUBULAR TIE.

1,075,249.

Specification of Letters Patent.

Patented Oct. 7, 1913.

Application filed September 12, 1912. Serial No. 719,942.

To all whom it may concern:

Be it known that I, JAMES C. GAYNOR, a citizen of the United States, and a resident of Paterson, in the county of Passaic 5 and State of New Jersey, have invented a new and Improved Woven Tubular Tie, of which the following is a full, clear, and exact description.

This invention relates to an improved 10 weave and a product secured thereby, and has for an object to provide such a woven fabric as to produce spaced tubular members in continuous fabric.

Another object of the invention is to provide a fabric in a continuous strip arranged 15 with spaced tubular portions and an extra or supplemental portion opposite each tubular portion.

In carrying out the objects of the invention, a fabric is provided having the usual 20 number of warp threads for making an ordinary tight weave, and also is provided with the usual number of weft threads. At spaced intervals part of the warp threads 25 are separated, and also the weft threads are separated, so as to form two layers of fabric. This double layer of fabric is provided at spaced intervals so that the same may be severed into independent tubular members for forming neckties and the like. In order to provide a filling member for the 30 necktie or tubular portion of the fabric some of the warp threads are used together with an independent weft thread for weaving a third layer adjacent the double layer 35 of fabric. From this it will be seen that the warp threads at spaced intervals form, together with the weft threads, a tight or taffeta weave, and between the tight weaves the warp threads are caused to diverge and 40 form the warp threads of three independent layers of fabric. Two of these layers are provided with weft threads from the same shuttle that is used for making the taffeta weave, while the third layer of fabric is 45 provided with weft threads from an independent shuttle.

A practical embodiment of the invention is represented in the accompanying drawings 50 forming a part of this specification, in which similar characters of reference indicate corresponding parts in all the views.

Figure 1 is a plan view showing a finished tubular necktie; Fig. 2 is a fragmentary perspective view of a section of 55 the fabric of which the tie shown in Fig.

1 forms a part; Fig. 3 is a section through Fig. 2 approximately on the line 3—3; Fig. 4 is a section through Fig. 1 on the line 4—4, the same being shown on an enlarged 60 scale; and Fig. 5 is a fragmentary plan view showing one end of the fabric embodying the invention.

Referring to the accompanying drawings by numérals, 1 indicates a complete necktie 65 provided with reinforcing strips 2 of fabric used for giving body to the tie. In weaving the necktie 1 the warp threads 3 are caused to extend in the usual manner longitudinally of the fabric but the weft threads 4 70 are arranged in a new way for providing a plurality of taffeta or tight weaves 5 and independent layers of fabric 6 and 7.

In weaving the fabric any number of shuttles may be used but the same shuttles 75 which place the weft threads in the taffeta weaves 5 place the weft threads in the layers of fabric 6 and 7, while one or more independent shuttles place the weft threads 8 in the filling or auxiliary layer 2 in position. The way the warp threads 3 are arranged may be varied to a large extent without departing from the spirit of the invention provided the same form part of the layers 6, 7, and 8. However, one way 80 of the weaving has been shown in the accompanying drawings in which the first pair of warp threads 3 is woven back and forth in the tight weaves 5 in the usual manner and then is woven back and forth 90 in the usual manner in the layer 7. The next succeeding pair of warp threads 3 is woven in the layer 8 and the third pair of warp threads 3 is woven in the layer 2.

It should be understood that any two of 95 the warp threads are woven back and forth in the usual manner in the taffeta or tight weaves 5, and then separated so as to extend into the respective layers 2, 6, and 7. As layer 2 is only a filling layer for providing a suitable padding for the tie, it is 100 not always necessary or desirable to use each third pair of warp threads for the same, but each sixth pair or any other proportion may be used without departing 105 from the spirit of the invention, enough of the warp threads being used; however, to properly hold the weft threads 8 in position. In placing the weft threads 8 in position, the shuttle is preferably caused to 110 turn back at point 9 (Fig. 1) so as not to provide a filling in the neck portion 10 of

the tie 1. In forming the neck portion 10, the same may be made of the same width as the body portion of the tie, or may be of less width, as clearly shown in Fig. 1. After 5 a strip of fabric 11 (Fig. 5) has been woven, the various ties 1 may be removed by merely cutting the fabric along the line of the taffeta or tight weaves 5 so as to leave a 10 part of the tight weave 5 as an edge for a necktie. The various neckties are then turned so that the edges 12 and 13 as well as the layer 2 will be placed within the layers 6 and 7, as shown in Figs. 1 and 4. This completes the tie without requiring 15 any sewing or the insertion of any extra filling matter.

In forming the weave any desired configuration may be produced in the usual manner and any desired number of shuttles 20 may be used. When the warp threads divide for forming the layers 6 and 7 the same number of shuttles may be used as when weaving the single layer or tightly woven portion 5, or additional shuttles may 25 be inserted for supplying a larger number of weft threads. Of course it will be evident that a less number of shuttles could be used although the same is not usually desirable.

30 Having thus described my invention I claim as new and desire to secure by Letters Patent:—

1. A strip of woven fabric comprising a plurality of tightly woven or taffeta portions 35 extending transversely of the strip from one edge to the other, and a woven tubular tie arranged between each pair of said tight or taffeta portions, said ties extending parallel with said tight or taffeta 40 portions and being woven with a double portion at the center and with more than a double portion at the ends whereby a filling structure is provided at the ends.

2. A strip of woven tubular ties, each of 45 said ties extending transversely of the strip and each tie in the weaving being formed with a single tubular portion at the central or neck portion of the tie and with tubular 50 portions and lining portions between the neck portion of the tie and the edges of the strip, said lining portions being superimposed on the tubular end portions of the tie, said lining portions having a selvage edge at each end, and each of said ties having 55 a selvage edge at each of the ends.

3. A strip of woven tubular ties, each of 60 said ties extending transversely of the strip and each tie in the weaving being formed with a single tubular portion at the central or neck portion of the tie and with tubular 65 end portions and lining portions between the neck portion of the tie and the edges of the strip, said lining portions being superim-

posed on said tubular end portions and each of said ties having a selvage edge at each end thereof.

4. A strip of woven tubular ties, each of said ties extending transversely of the strip and each tie in the weaving being formed with a single tubular portion at the central 70 or neck portion of the tie and with tubular end portions and woven lining portion between the neck portions of the tie and the edges of the strip, said lining portions being superimposed on said tubular end portions 75 each of said ties having selvage edges at each end and said filling portions having a selvage edge at each end of the tie.

5. In a weave of the class described, a plurality of spaced tightly woven portions 80 extending transversely of the strip being woven, a transversely arranged tubular portion positioned between each of said tightly woven portions, the position of the tubular portions transversely of the strip causing 85 the ends of the tubular portion to be formed with a selvage edge, and an extra woven lining arranged between each of said tightly woven portions so as to lie adjacent said tubular portions, said lining being superimposed on the end portions of said tubular portion, said lining, being formed with a selvage edge adjacent the selvage edge of the strip being woven.

6. A woven fabric formed tubular in 95 shape with a selvage at each end, said fabric being restricted or reduced in size centrally, and an auxiliary woven layer having a selvage at each end woven adjacent the tubular fabric and extending from the selvage of the fabric to the reduced central portion said auxiliary woven layer being superimposed on the end portions of the tubular fabric.

7. In a woven tubular tie, a body portion 105 formed with a pair of oppositely arranged woven layers merging together at opposite edges and at said edges forming a taffeta woven portion, said taffeta woven portion extending transversely of the body, and an 110 auxiliary woven layer arranged adjacent said body portion with its warp threads extending through said taffeta woven portion and forming a part thereof, the weft threads of said filling layer forming a selvage upon 115 each edge of said body and extending from the opposite edges of said body to a point less than half the width of the body.

In testimony whereof I have signed my name to this specification in the presence of 120 two subscribing witnesses.
